Patented December 22, 1903.

UNITED STATES PATENT OFFICE.

DWIGHT H. WAGNER, OF WHEELING, WEST VIRGINIA, ASSIGNOR TO WHEELING CORRUGATING COMPANY, OF WHEELING, WEST VIRGINIA, A CORPORATION OF WEST VIRGINIA.

DESIGN FOR A SHEET-METAL FIELD-PLATE FOR CEILINGS AND MOLDING THEREFOR.

SPECIFICATION forming part of Design No. 36,703, dated December 22, 1903.

Application filed November 16, 1903. Serial No. 181,446. Term of patent 7 years.

To all whom it may concern:

Be it known that I, DWIGHT H. WAGNER, a citizen of the United States of America, and a resident of Wheeling, county of Ohio, and 5 State of West Virginia, have invented a certain new, original, and ornamental Design for Sheet-Metal Field-Plates for Ceilings and a Molding Therefor, of which the following is a specification, reference being had to the accompanying drawing, forming part hereof.

The figure is a plan view of a plate, showing my new design.

What I claim as new, and desire to secure by Letters Patent, is—

The ornamental design for sheet-metal field- 15 plates for ceilings and a molding therefor, as herein shown.

DWIGHT H. WAGNER.
